UNITED STATES PATENT OFFICE.

PAUL E. DUBREUIL, OF BALTIMORE, MARYLAND.

SHIRT.

SPECIFICATION forming part of Letters Patent No. 240,676, dated April 26, 1881.

Application filed March 2, 1880. (No model.)

To all whom it may concern:

Be it known that I, PAUL E. DUBREUIL, of the city of Baltimore, State of Maryland, have invented certain new and useful Improvements 5 in Shirts; and I do hereby declare that the following is a full, clear, and exact description of the same.

My invention relates to shirts, preferably of that class which are made with a closed front. 10 and open upon the back. This class of shirts (more desirable in some respects than those opening upon the front) are objectionable in this respect, that the wearer has no access to his bosom when the shirt is on, and this often 15 occasions great inconvenience, and sometimes very great irritation. Furthermore, in warm weather, shirts of this class often occasion a great discomfort to the bosom of the wearer by reason of the heat and lack of ventilation. 20 My invention consists of the particular arrangement of opening by which the hand may be introduced underneath the shirt-front without soiling the bosom, and by which also the shirt-front is ventilated. 25 Heretofore attempt has been made to remedy this difficulty by leaving open a portion of the seam between the bosom of the shirt and the side of the shirt-front which it adjoins. This opening would serve the purposes for admitting 30 the hand and of ventilation; but it is rendered impracticable for the reason that that part of the bosom not attached to the shirt-front is very difficult to be properly laundered, and is almost certain to be wrinkled and bruised by 35 the iron. Further, with this particular construction the shirt is liable to be torn, and the exposed edges would soon become frayed and unsightly. Further than this, the opening would ordinarily be too near the center of the 40 bosom for concealment.

In my improved shirt the bosom is inserted in the front and connected in the ordinary manner. It is represented in the drawings at C.

Upon one side of the front, preferably about midway between the edge of the bosom and 45 the armpit, I make an opening, D, which, as shown in Fig. 1, is curved, with its convex edge toward the bosom. This is the preferred form, for the reason that thereby the outside flap, the loose edge of which is concave, retains its form better, and is less liable to 50 wrinkle. This opening is made large enough to admit freely the hand. It will be understood that the flap covers the opening and conceals it from view. 55

It is not absolutely necessary that the opening be in the curved form. It may be made straight, as shown in Fig. 2, but in this case it should be provided with the button e.

I prefer to use a re-enforcement upon the front, 60 as shown in the figures, the lower edge of the re-enforcement being indicated by the lines a a, and with this re-enforcement the opening and the flap which covers it are retained more firmly in place, and this construction makes a 65 better appearance.

I am aware of the patents granted to T. Green, of September 19, 1876, and also that granted to J. S. Lester, of March 30, 1880, and desire to have it understood that I limit my 70 claims to the specific construction and arrangement shown by me.

Having thus described my invention, what I claim is—

The described shirt having a bosom, C, completely attached to the shirt-front, in combination with the opening D, formed in the shirt-front between the edge of the bosom and the armpit, substantially as described. 75

In testimony whereof I affix my signature 80 in presence of two witnesses.

PAUL E. DUBREUIL.
